CHRISTMAS BOOT

Kittie M. Glascock, 1234 S. Atlanta Place, Tulsa, Okla.,
assignor of thirty percent to Flavia M. Durfey, Tulsa, Okla.

Filed Apr. 1, 1960, Ser. No. 59,990

Term of patent 14 years

(Cl. D47—7)

Fig. 1

Fig. 2

FIG. 1 is a front elevational view of a Christmas boot showing my new design;

FIG. 2 is a side elevational view thereof;

FIG. 3 is a top plan view thereof; and

FIG. 4 is a rear elevational view of the same.

The ornamentation on the left rear of the boot in FIG. 4 is like that on the right and in proper relationship thereto.

I claim:

The ornamental design for a Christmas boot, as shown and described.
